DESIGN FOR LADY'S ADJUSTABLE GIRDLE

Nathan Appelbaum, New York, and Sarah
Shron, Brooklyn, N. Y.

Application March 4, 1936, Serial No. 61,480

Term of patent 3½ years

To all whom it may concern:

Be it known that we, Nathan Appelbaum, a citizen of Poland, and Mrs. Sarah Shron, nee Podbielewitz, a citizen of the United States, the former residing at New York, in the county of Bronx and State of New York, and the latter at Brooklyn, in the county of Kings and State of New York, have invented a new, original, and ornamental Design for a Lady's Adjustable Girdle, of which the following is a specification, reference being had to the accompanying drawing, forming part thereof.

In the drawing:

Fig. 1 is a front elevation of the adjustable girdle, showing our new design.

Fig. 2 is an inner rear view of the same.

We claim:

The ornamental design for lady's adjustable girdle, as shown.

NATHAN APPELBAUM.
SARAH SHRON.
